CLAIM

An ornamental design for a male hose coupling, as shown and described.

DESCRIPTION

FIG. 1 is a front perspective view of a male hose coupling;
FIG. 2 is a side view of the male hose coupling;
FIG. 3 is a front view of the male hose coupling;
FIG. 4 is a rear view of the male hose coupling; and
FIG. 5 is a rear perspective view of the male hose coupling;
and,
FIG. 6 is a partial cross-sectional view taken along line 6-6
of FIG. 2.

The broken lines in the drawings depict portions of the male
hose coupling that form no part of the claimed design.
